UNITED STATES PATENT OFFICE

2,427,035

SHELL HANDLING DEVICE FOR TRENCH MORTARS

Erving M. Wilcoxon, Centralia, Wash.

Application December 1, 1942, Serial No. 467,539

14 Claims. (Cl. 89—1)

(Granted under the act of March 3, 1883, as amended April 30, 1928; 370 O. G. 757)

1

The invention described herein may be manufactured and used by or for the Government for governmental purposes, without the payment to me of any royalty thereon.

This invention relates to a shell handling device, particularly to a device for loading trench mortar shell into the muzzle from a magazine.

It has been the custom in trench mortar firing to handle the shell individually, dropping a shell into the muzzle of the inclined barrel and relying upon gravity to accelerate the shell to a velocity sufficient to detonate the propellant charge on impact. Mortar firing based on this principle has a number of inherent disadvantages, the first of which is that the mortar cannot be operated below a predetermined minimum elevation. Another objection to this method of mortar firing is that it is slow and cumbersome.

It is an object of this invention to provide a device which may be attached to a trench mortar to permit firing of the mortar at any elevation, and to permit a rapid and uniform rate of firing. This is accomplished by a spring biased fork to grip the shell and force it into the muzzle at a given velocity in addition to its velocity due to gravity. The fork operates in a slotted guide which is secured to the muzzle of the barrel and is aligned with it. An enlargement at the point of attachment permits withdrawal of the fork and release of the shell, which continues on to the bottom of the barrel where the propellant charge is detonated. A trigger holds the fork in shell-receiving position. A magazine feeds shells to the guide and is provided with a stop to keep the shells away from the muzzle except when it is desired to feed a shell to the guide.

The specific nature of the invention as well as other objects and advantages thereof will clearly appear from a description of a preferred embodiment as shown in the accompanying drawings in which:

Fig. 1 of the drawings is a view in horizontal longitudinal section of a mortar muzzle with the invention attached.

Fig. 2 is a plan view of Fig. 1, showing details not disclosed in Fig. 1.

Fig. 3 is a view in elevation of the invention.

Fig. 4 is an end elevation view, with the trigger removed.

Fig. 5 is a side elevation detail view of the stop.

Referring now to the drawings in detail, 2 indicates the muzzle of a trench mortar or similar gun barrel to which the invention is shown attached. A guide 4 is provided with a collar 6 which fits snugly over the muzzle end of the 55

barrel, holding the guide in alignment with the barrel. The guide is slotted as at 8 to receive shell engaging means such as sliding block 10 carrying the forks or fingers 12 and provided with a handle 14. Block 10 is movable in slot 8 axially of the barrel 2. Near the point of attachment of guide 4 to barrel 2, the guide is enlarged outward radially, as at 16, to permit withdrawal of shell engaging forks 12 from the shell as the latter is projected backward into the barrel. Shells are shown in dot and dash lines at 18.

Block 10 is preferably provided with spring mounted rollers 20 to facilitate its sliding along guide 4. A tension spring 22 biases block 10 toward the gun. Latch or trigger means 24 may be provided to retain block 10 forward against the bias of spring 22. A cord 26 may be attached to the trigger to provide means for easy disengagement of the trigger from the block.

20 A magazine 28 is provided to hold shell 18 for feeding to guide 4. As can best be seen in Fig. 4, guide 4 is substantially semi-circular in cross section, with its open face toward the right as seen in Fig. 4. Magazine 28 is mounted to feed shells to this open face. A stop 30 is preferably provided to keep shells from being moved into alignment with the mortar barrel. Stop 30 preferably consists of a substantially rectangular plate, as seen in Fig. 5, having an extending arm 32 adapted to be secured in non-rotating relation to one end of a shaft 34. The other end of the shaft carries a pinion 36 which meshes with a rack 38. Rack 38 is preferably integral with a reciprocable rod 40, mounted in bearings 42 on the guide 4. Shaft 34 is rotatable by the rack and pinion in bearings 44 and 46. An upright rod 48 on rod 40 is positioned to be engaged by handle 14. A spring 50 on rod 40 may be provided to urge stop 30 downward when handle 14 is pulled out of engagement with rod 48.

To insure proper alignment of each shell with the barrel, guide extension 52 is provided in enlargement 16 of guide 4. Shells may be fed toward guide 4 from the magazine by gravity, for which purpose the magazine will be inclined, or by a magazine spring, not shown.

Operation.—With shells in the magazine, kept from the barrel by stop 30, handle 14 is pushed forward against the bias of spring 22, moving rod 40 and rack 38 forward and raising stop 30 against the bias of spring 50. A shell rolls into position against guide 4 and is engaged by forks 12. If a latch 24 is provided, handle 14 and block 10 are held in the position shown in the drawings. When it is desired to fire the mortar, handle 14

and block 10 are released for movement by spring 22. Where a latch or trigger is used, this involves pulling the trigger to release the block. Forks or fingers 12 thereupon carry the shell rearward into mortar barrel. As block 10 nears the muzzle, it is carried radially outward into enlargement 16, removing forks 12 from engagement with the shell and permitting the latter to continue to the end of the barrel under the momentum imparted to it by spring 22.

Meanwhile, stop 30 has been dropped down to hold the next shell away from the mortar muzzle.

If desired, the teeth at the inner end of rack 38 may be cut away, to permit stop 30 to drop back into place after a shell has been released to the guide. In that case, a suitable ratchet or the like would be provided to permit pinion 36 to rotate loosely on the shaft for the firing stroke of the handle 14 and rack 38.

I claim:

1. Projectile handling mechanism comprising: a guide adapted to be positioned at the muzzle of a gun barrel, a magazine positioned to feed projectiles to the guide, projectile engaging means on the guide mounted for movement in a direction parallel to the axis of the gun barrel and constructed and arranged to exert a rearward force upon a projectile, a spring to bias the engaging means toward the muzzle of the barrel, and a latch to hold the engaging means against movement by the spring.

2. Projectile handling mechanism comprising: a slotted guide adapted to be positioned at the muzzle of a gun barrel, a magazine positioned to feed projectiles to the guide, projectile engaging means mounted in the slot of the guide for movement axially of the barrel and constructed and arranged to exert a rearward force upon a projectile, a spring to bias the engaging means toward the muzzle of the barrel, and a latch to hold the engaging means against movement by the spring.

3. The invention of claim 2, in which the guide is enlarged near its point of attachment to the muzzle to permit retraction of the engaging means.

4. In projectile handling mechanism, a guide adapted to be positioned at the muzzle of a gun barrel and aligned with it, a magazine positioned to feed projectiles to the guide, projectile engaging means on the guide mounted for movement in a direction substantially parallel to the axis of the barrel and constructed and arranged to exert a rearward force upon a projectile, a spring to bias the engaging means toward the muzzle of the barrel, a stop to keep projectiles from moving into loading position on the guide, means responsive to the movement of the projectile-engaging means against the bias of the spring to move the stop to an inoperative position in which it permits a projectile to be moved into loading position on the guide, and a latch to hold the engaging means against movement by the spring.

5. In projectile handling mechanism, a slotted guide adapted to be positioned at the muzzle of a gun barrel, a magazine positioned to feed projectiles to the guide, projectile engaging means mounted in the slot of the guide for movement axially of the barrel, a spring to bias the engaging means toward the muzzle of the barrel, a stop to keep projectiles from moving into loading position on the guide, means to move the stop responsive to the movement of the projectile-en-

gaging means against the bias of the spring to move the stop to an inoperative position in which it permits a projectile to be moved into loading position on the guide, and a latch to hold the engaging means against movement by the spring.

6. A mortar shell loading device comprising a guide adapted to be secured to the muzzle of a mortar barrel, a magazine on the guide adapted to feed shells to the guide, a shell engaging element adjacent said guide for moving a shell from said guide into said mortar barrel, a spring to bias the element toward the muzzle, and a trigger to hold the element in position to receive a shell from said magazine.

10 7. A mortar shell loading device comprising a guide adapted to be secured to the muzzle of a mortar barrel, a magazine on the guide adapted to feed shells to the guide, a shell engaging element movable on the guide axially of the mortar barrel, a spring to bias the element toward the muzzle, a stop to keep shell from moving into loading position on the guide, and means to move the stop to permit a shell to move into loading position upon movement of the engaging element against the bias of the spring.

15 8. The invention of claim 7, and a trigger to hold the element in shell receiving position against the bias of the spring.

9. A projectile handling mechanism: comprising 20 a guide adapted to be positioned at the muzzle of the gun, projectile-engaging means on the guide mounted for movement in a direction parallel to the axis of the gun barrel and constructed and arranged to exert a rearward force on a projectile, and spring means to bias the engaging means toward the muzzle of the barrel with sufficient force exerted longitudinally of the barrel to feed the projectile through the guide into the muzzle of the gun.

40 10. A projectile handling mechanism: comprising a slotted guide adapted to be positioned at the muzzle of a gun barrel, a magazine positioned to feed projectiles to the guide, projectile-engaging means mounted in the slot of the guide for movement axially of the barrel and constructed and arranged to exert a rearward force on a projectile, and a spring to bias the engaging means toward the muzzle of the barrel with sufficient force exerted longitudinally of the barrel to feed the projectile through the guide into the muzzle of the gun.

45 11. A mortar shell loading device: comprising an open sided guide adapted to be secured to the muzzle of a mortar barrel, a magazine on the guide positioned to feed shells into the open side of the guide, a shell-engaging element adjacent said guide for moving a shell from said guide into said mortar barrel, and spring means to bias the element toward said muzzle with sufficient force applied longitudinally of the barrel to feed the projectile through the guide into the muzzle of the gun.

50 12. In combination with a mortar barrel, a magazine attached to the end of said barrel, an open-sided guide positioned at the end of said barrel to receive the projectile from the magazine, and spring means placeable in tension longitudinally of said barrel for urging the projectile 55 out of the guide into the barrel of the mortar.

60 13. In combination with a mortar barrel, a magazine for projectiles attached to the muzzle of said barrel and spring means exerting a force longitudinally of the barrel for feeding a projectile from said magazine into said barrel and for 65 70 75

forcing it to travel to the breech end of said barrel.

14. In combination with a mortar of the trench mortar type, a magazine for projectiles therefor at the muzzle end thereof, and means, including spring means placeable in tension longitudinally of the mortar barrel, for impelling projectiles from said magazine into said mortar towards the breech end thereof.
